UNITED STATES PATENT OFFICE.

WILLIAM O. BEMENT, OF WORCESTER, MASSACHUSETTS.

METALLIC MAT OR FLOOR-COVERING.

SPECIFICATION forming part of Letters Patent No. 377,478, dated February 7, 1888.

Application filed October 4, 1887. Serial No. 251,429. (No model.)

To all whom it may concern:

Be it known that I, WILLIAM O. BEMENT, a citizen of the United States, residing at Worcester, in the county of Worcester and State of Massachusetts, have invented certain new and useful Improvements in Metallic Mats or Floor-Coverings, of which the following is a specification, reference being had thereto in the accompanying drawings.

The object of my invention is to provide a metallic door-mat, which may be made at little cost, and which will be of such construction that it will not injure the boots or shoes of the users, which is reversible, so that it may be used either side up, and which, while sufficiently flexible to adapt itself to uneven floors, so as to lie smoothly thereon, is sufficiently stiff in the direction of the strain to which it is subjected in use to resist objectionable distortion or displacement.

To this end the body of my mat consists of flattened metallic strips, both edges of which are slightly rounded, so that the scraping-surfaces afforded thereby will not injure the boots or shoes of the users, said strips being placed edgewise and secured a suitable distance apart to permit the scrapings to fall between them. These scraping-strips, which are preferably parallel to each other and extend lengthwise of the mat, are perforated at intervals for the passage of comparatively small transverse rods or wires on which sleeves are placed between the strips to hold the latter separated. The sleeves may consist of plain metallic ferrules or collars or short lengths of coiled wire. At the outer sides of the mat and parallel with the scraping-strips are comparatively heavy longitudinal rods or bars which stiffen the mat and hold it from displacement against the strain of scraping, and the transverse rods (which are sufficiently small to render the mat somewhat flexible, so that it will adapt itself to uneven floors) are riveted or otherwise secured at their outer ends to the said heavy rods.

In the drawings, Figure 1 is a plan view of my improved mat. Fig. 2 is a detail section on line *a* of Fig. 3. Fig. 3 is a detail plan view on a larger scale than Fig. 1. Fig. 4 is a partial section on line *b*, Fig. 3. Fig. 5 is a de-

tail view showing a modification. Fig. 6 is a plan view to show how very large mats may be made from smaller ones.

The scraping-bars of the mat consist of the flat strips *c*, both edges of which are preferably rounded, as shown in Fig. 2, so that the scraping-surfaces afforded by said edges will not injure the boots or shoes of the users. These strips are held in place by the comparatively small transverse rods or wires *d*, which pass through holes formed at proper intervals in the said strips, and the latter are held separated from each other by sleeves, which may be plain ferrules, *e*, or small coils of wire, *e'*. The rods *d*, being comparatively small, are somewhat flexible, so that the mat by its own weight will adapt itself to any unevenness of the floor on which it may be laid, and will therefore not rock or jolt when stepped on. Parallel with the strips *c* on the outer sides of the mat are the strengthening rods or bars *f*, to which the ends of the transverse rods *d* are secured by riveting or otherwise, the said rods or bars *f* being much heavier than the rods or wires *d*, all of which latter (including those at the ends of the mat) are flexible, as above stated. The stiff rods or bars *f* serve as resistance-bars to prevent objectionable distortion of the mat when in use, the strain on the mat in scraping being transverse of the strips *c* and rods *f*, as will be understood. If this strain is excessive, the rods *f* may bend slightly when subjected thereto, but they will immediately spring back into place when the scraping strain ceases, and thus the flexible mat will always be kept in proper shape.

As both edges of the strip *c* are rounded, the mat will be alike on both sides, so that either side of the mat may be used, or it may be reversed when desired. These strips *c* are preferably of flattened wire, which when rolled down leaves both edges smooth and rounded, as shown in Fig. 2; but these rounded-edged strips may be made by drawing or otherwise, if desired. The diameter of the sleeves *e* and *e'* is preferably less than the width of the strips *c*, so that the scraping-surfaces of the mat will not be interrupted by the said sleeves.

To make a large mat, as shown in Fig. 6, several smaller ones may be secured together

by metallic hooks or links *g*, this plan being adopted when the mats are placed at wide doorways or stairways.

These mats may be advantageously used whenever grated floor-coverings are desired, and for this purpose they are particularly well adapted for horse-cars and other public vehicles. As these mats are usually made the strips *c* are so close together that a dime (the 10 smallest coin now in general circulation) cannot lie flatwise between them, so that if any coin be accidentally dropped on the floor of a vehicle provided with these coverings it will not fall entirely through the covering, but will 15 usually stand up partly edgewise between the strips *c* and can easily be picked up, and thus annoyance incidental to the loss of coins through the grated floor-coverings now in use in street-cars will be avoided.

20 From the foregoing it will be apparent that my improved mat combines the advantages of cheapness of construction and convenience in use with great durability.

I am aware that it is not broadly new to 25 make mats the bodies of which consist of strips of metal set up edgewise and separated from each other; but so far as I am aware I am the first to make a flexible mat of this kind which will readily adapt itself to uneven floors, or a 30 metallic mat having scraping strips the edges of which are rounded on both sides of the mat, so that the shoes of the users will not be injured in scraping, and so that the mat may be

used either side up or reversed when desired.

Having thus described my invention, I claim 35 and desire to secure by Letters Patent—

1. A metallic mat or floor-covering consisting of the combination of the parallel flat strips *c*, both edges of which are rounded, a series of flexible transverse rods or wires, *d*, 40 passing through the said strips, two outer longitudinal side strengthening-bars, *f*, larger than the transverse rods or wires *d*, and a series of sleeves on the said rods or wires *d*, between the said strips *c*, to hold the latter separated, substantially as set forth. 45

2. A metallic mat or floor-covering consisting of the combination of the parallel flat strips *c*, both edges of which are rounded, a series of flexible transverse rods or wires, *d*, 50 passing through the said strips, two outer longitudinal side strengthening-bars, *f*, larger than the transverse rods or wires *d*, and a series of sleeves on the said rods or wires *d*, between the said strips *c*, to hold the latter separated, the diameter of the said sleeves being less than the width of the said strips, so that the scraping-surfaces afforded by the edges of the latter will not be interrupted, substantially as set forth. 55

In testimony whereof I affix my signature in presence of two witnesses.

WILLIAM O. BEMENT.
